UNITED STATES PATENT OFFICE.

CHRISTIAN BRYNOLDT, OF PITTSBURGH, PENNSYLVANIA, ASSIGNOR TO BLAW-KNOX COMPANY, A CORPORATION OF NEW JERSEY.

CONSTRUCTION OF DAMS.

Application filed October 25, 1922. Serial No. 596,816.

To all whom it may concern:

Be it known that I, CHRISTIAN BRYNOLDT, a citizen of the United States, residing at Pittsburgh, in the county of Allegheny and State of Pennsylvania, have invented certain new and useful Improvements in the Construction of Dams, of which the following is a specification.

My invention relates to the construction of dams, embankments, and the like, and affords novel methods and apparatus for that purpose. It is particularly advantageous for the building of concrete dams and embankments.

Heretofore, such structures have been built in rather piecemeal fashion, generally by the construction of a number of more or less separate or isolated blocks, which were begun, carried on, and completed pretty much as individual units. This mode of construction is subject to very serious drawbacks, however, in that, first, it entails setting up and taking down again the forms and much of the other equipment for each and every such block of the dam,—a very laborious and costly proceeding,—and secondly, in that the forms are nearly always in the way of the concrete mixing and conveying apparatus. In general, the method is essentially inconsistent with arranging and co-ordinating equipment and operations in such a way as to secure any great degree of convenience, expedition, or economy.

It is a prime object of my present invention to overcome all such difficulties, and to enable dam-building to be carried on in an orderly, convenient, expeditious, and economical manner. This I aim to accomplish by a wholly different system of construction, which not only allows very convenient and economical types of traveling forms to be employed and facilitates the actual setting up and filling of the forms, but also affords much greater convenience in the arrangement and use of the equipment generally, and much greater facility for conveying and handling both concrete and equipment. I also aim to provide apparatus and equipment that will expedite, facilitate, and cheapen the various operations involved in and by themselves.

How these and other advantages can be realized through the invention will appear from my description hereinafter of the best methods and apparatus for its purposes that

are known to me. However, the detailed description will be rendered clearer and more readily intelligible by a brief preliminary outline of my preferred methods of procedure,—which, as will appear, admit of considerable variation.

As will be seen hereinafter, the common broad idea of the various modes of carrying out my invention that I shall presently proceed to describe is the construction of a wall (or walls) which may afterward form a part of the completed dam, and the completion or filling out of the dam to its full section or thickness beside this wall. Such a preliminary wall may be easily and quickly built up ahead of the rest of the dam (preferably with a traveling form), and may then serve as a convenient pathway and means of support for the subsequent filling in and other operations, and even, indeed (ultimately) as a foundation for upper portions of the dam. This preliminary wall may be started at any elevation, as soon as sufficient footing or foundation is in place in the dam site; and it may either be completed to its full height at the outset (even to the very top of the dam), or built up progressively, as the rest of the dam is filled in against it. Such a wall may occupy various positions in the dam: thus it may form the front or upstream face of the dam, and the rest of the structure be filled in behind it (see Figs. 4 and 5 of my drawings); it may form the central portion of the dam, the rest of which will then be filled in both in front and behind (Fig. 12); or there may be two such walls, one at each face of the dam, and the structure may be completed by filling in between them (Figs. 13, 14, and 15). Which of these variant modes of construction should be preferred in practice depends, of course, on the cross section of the dam to be built, and also on other considerations peculiar to each particular case: indeed, different modes may sometimes be employed to good advantage in different longitudinal or vertical sections of the very same dam. Oftentimes, too, the preliminary wall may be stopped when a certain height is reached, and the upper portion of the dam completed as one cross sectional unit (Fig. 11), preferably by means of a suitable traveling form.

In the drawings, Fig. 1 shows a cross section through the bed of a stream, and

illustrates in side elevation a rather early stage in the construction of a dam according to my invention.

Fig. 2 is a similar view illustrating a more advanced stage in the construction of the dam.

Fig. 3 is a plan view of the dam at a somewhat more advanced stage than that illustrated in Fig. 2.

10 Fig. 4 is a cross sectional view, taken as indicated by the line 4-4 in Fig. 1, but on a larger scale and with certain parts omitted, illustrating one stage in the construction of a dam according to the "facial wall" variation of my preliminary wall method.

Fig. 5 is a view similar to Fig. 4, taken as indicated by the line 5-5 in Fig. 2, but showing a somewhat less advanced stage of operations than shown in Fig. 3.

20 Fig. 6 is a cross sectional view, taken as indicated by the line 6-6 in Fig. 2, illustrating the arrangement of apparatus for supplying concrete from a mixer (not shown) for construction of the dam.

25 Fig. 7 is a fragmentary horizontal sectional view, taken through a form as indicated by the line 7-7 in Fig. 4, illustrating the moulding of anchor bolts into the concrete.

30 Fig. 8 is a fragmentary plan view, taken as indicated by the line 8-8 in Fig. 2, but on a larger scale, illustrating certain features of the form structures and associated parts.

35 Fig. 9 is a fragmentary vertical sectional view, taken as indicated by the line 9-9 in Fig. 8.

Fig. 10 is a view showing the dam completed to the full height indicated in Fig. 2.

40 Fig. 11 is a cross sectional view somewhat similar to Figs. 4 and 6, illustrating the building of the top portion of a dam as one cross sectional unit, by means of a traveling form.

45 Fig. 12 is a cross sectional view corresponding to Figs. 4 and 6, but illustrating the construction of a lower portion of a dam by the "central wall" variation of my preliminary wall method.

50 Fig. 13 is a somewhat similar view illustrating an early stage in the "double wall" variation of my method, as applied to the construction of the lower portion of a dam by means of traveling forms.

55 Fig. 14 is a somewhat similar view illustrating a somewhat later stage in the same form of my method, and showing apparatus for closing the end of a wall space that is also useful for the construction of the preliminary wall in other forms of my method.

60 Fig. 15 is a fragmentary plan view corresponding to Fig. 14, but with certain parts omitted.

65 In Fig. 1 the dam site is shown with the foundations A built or prepared for its en-

tire length up to the level of the irregular broken line. In the bed of the stream, an additional concrete footing or base structure B has been built up to the level of the lowermost full horizontal line, with an opening C therethrough for the stream flow. On the footing A, B, the preliminary concrete wall D has been built up to about the height of the rails 21 all the way across the stream bed, and has been carried on up to the higher level shown for nearly half the intended length of the dam. As will be seen from Figs. 1, 2 and 3, the latter portion of this wall D has been built in monolithic sections d interengaged and interlocked with tongue 75 and groove construction joints, and a couple of sets of units of traveling wall form apparatus 24 are in place for the construction of an additional wall section d adjacent the center of the dam. The track or rails 21 on which the wall form apparatus 24 runs have been extended all the way across the stream bed, being laid on longitudinal stringers 25 resting on supports 26 which are themselves laid on the footing B or secured bracket-wise (as by anchors 27 embedded in the concrete) to the lowermost portion of the wall D, in the manner indicated in Figs. 4 and 5. On the pathway afforded by the top of the wall D have been laid a couple of tracks 85 (see Figs. 1 and 3) for cars 29 for supplying concrete to fill the wall forms at 24. As shown, these cars 29 are loaded from overhead bins or hoppers 30 themselves served by a gravity hopper and chute 31, to which the loose green concrete is continually elevated and delivered from any suitable mixing plant or apparatus (not shown) by inclined tower and conveyor mechanism 32,

95 all as illustrated in Fig. 6. (We here use the expression "loose" in reference to the lack of cohesion of freshly mixed concrete, before it has set,—without any implication as to existence of voids or want of compactness.) 105 In Fig. 2, the row of wall sections d has been extended and completed the full length of the dam, and a second series of similar wall sections d' has been built on top of them from the right hand end of the dam 110 nearly to the middle,—where the traveling wall form apparatus 24 is shown in place for the construction of an additional section d'. As shown in Fig. 5, the upper and lower wall portions d' and d are interengaged and interlocked with double tongue 115 and groove construction joints. The track 21 with its bracket supports 26 has been raised from its position in Fig. 1 to about the top of the wall portion d' and greatly extended, so as to be available for the travel 120 of the wall form 24 and of apparatus 35 for filling in loose green concrete beside the wall D the full length of the latter. As the track 28 has been removed from the top of 125 the older portion d to make way for the

new wall sections d' , it has been laid and extended along on top of the portion d' to carry cars 29 to serve the forms 24 on the raised track 21. Also, track 21 for traveling apparatus 35 for filling in concrete beside the wall D has been laid alongside the top of the portion d' , on bracket supports 26 secured to the latter. (If it be desired to carry the wall D on up another "lift", the upper track 21 will, of course, serve to support the wall forms 24 for that purpose.) Loading hopper, chute, and elevator apparatus 30, 31, and 32 such as shown in Fig. 6 and already described has been provided for serving the cars 29 on the upper track 28.

Referring now, more particularly to Fig. 4, it will be seen that each unit of the wall form apparatus 24 comprises a truss built traveler 40 of what may be termed a "straddling" type, with cooperating steel plate wall forms 41 laterally and vertically adjustable between its legs or sides 42 that rest and run on the track 21. Stay bolt rods 43 (that can be withdrawn after the concrete has set) may extend across between the legs 42 to prevent spreading apart of the forms 41. As shown, the whole apparatus 24 is properly set up on top of the lower wall portion d , ready to mould an upper wall section d' as illustrated in Figs. 2 and 3. Along the top of the traveler 40, lengthwise of the wall D, extend track lengths 44 that serve as extensions of the tracks 28 to receive the cars 29 and facilitate delivery of their concrete between the forms 41. As shown, a pair of such tracks 44 are suspended side by side from the transverse bridge structure 45 of the traveler 40 (by adjustable link rods 46), directly over the wall space between the forms 41. It will be seen, therefore, that the cars 29 may be either side or bottom dumping, since the one type can dump into the forms 41 between the adjacent pair of rails 44, and the other type between its own rails.

As shown in Fig. 7, the steel plate forms 41 are preferably provided with upright channels 47 (of double angle bar construction) at suitable intervals on their outer faces. The anchor bolts 27 that afterward secure the track supporting brackets 26 to the wall D are inserted in aligned holes in form plates and channel flanges before the forms 41 are filled with concrete, and thus become firmly embedded in the wall at the correct interval and height. Preferably, these anchor bolts 27 are double ended, with nuts 48 screwed on their embedded ends as well as securing nuts 49 for the brackets 26 on their projecting ends; so that eventually these bolts 27 can be unscrewed and removed, merely leaving the nuts 48 permanently embedded in the concrete.

Referring, now, to Figs. 2, 3, and 5, it will

be seen that the apparatus 35 for filling in the dam portion E in beside the wall D comprises a traveler 50 adapted (like the traveler 24) to be moved or run along the top of the wall D on the rails 21, over the car tracks 28, with ample clearance beneath for cars 29 running on said latter tracks. This traveler 50 is equipped with means for taking or receiving concrete from cars 29 underneath, and distributing it as required. As shown, there is a steam engine operated elevator comprising one or more hoppers or buckets 51 adapted to run up and down in ways 52 extending upward from beside the tracks 28, and to dump overboard into a hopper 53 as the hoisting cable 54 brings such bucket to the top of its upward course. The concrete can either be dumped sideways from cars 29 directly into the buckets 51, or else simply shovelled into these buckets. The hopper 53 is mounted on a sort of lateral boom structure 55, pivoted to the traveler at 56 to swing horizontally, and delivers into gravitational distributing means in the form of inclined troughs 57, 58. What with the swing of the boom 55 and the movement of the traveler 50 along the tracks 21, it will be seen, the concrete can be delivered and distributed at pleasure over a wide area beside the wall 20.

For the face of the dam remote from the wall D, I prefer to employ steel plate forms 60 such as shown in Figs. 2, 3 and 5, shiftable upward along the dam face as the concrete is filled in between them and the wall. As shown, each such form 60 has transverse angle bars 61 that extend some distance below the lower edge of the form plate, so that the form can be secured in place by anchor bolts 27 (just like those shown in Figs. 4 and 7) extending through the projecting lower ends of the bars 61. When the concrete is filled in behind and against the form 60, anchor bolts 27 mounted in the upper portion of the form (about as already described in connection with Figs. 4 and 7) become firmly embedded in the corresponding portion of the dam, ready to hold the form 60 in place when it is raised for the next fill,—exactly in the same way as illustrated in Fig. 5. As the forms 60 are raised, the anchor bolts 27 that have held them can be removed, just as already described in connection with Figs. 4 and 7. As shown in Figs. 2, 3 and 8, bulkhead forms 63 such as illustrated in Fig. 9 may be used with the dam face forms 60, and may be similarly provided with transverse, vertically extending angle bars 64. They may be secured to the concrete by bolts 27 in like manner, and may likewise carry other bolts 27 for embedding in the concrete to hold them in place when raised the next lift from their positions in Fig. 9. As shown in that figure, each bulkhead form 63 is made up of two

flange edged sections, one of which rests against the portion of the concrete that was filled in when the form was in its next lower position than that illustrated.

As shown in Fig. 4, the track supporting brackets 26 on the wall portion D are just above the footing B, and the wall D is about to be built up its lift or course *d* by filling in the form 24 as set up in Fig. 4: accordingly, the dam face form 60 is omitted, to signify its removal for use elsewhere. In Fig. 5, the wall portion *d* has been built on top of the lowermost wall portion or course; concrete E has been filled in alongside for about half its height; and the form 60 is in position for filling in up to the brackets 26. If (as indicated in Fig. 2) the dam is to be materially higher than this, the wall D may be carried up one or more additional lifts, and the dam portion E correspondingly filled in along side of it. The final course or topping of the dam may vary considerably. In the spillway portion especially, the top of the dam may often be built as a single cross sectional unit, more or less as hereinafter described. As shown in Fig. 10, however, the entire dam has simply been filled in and levelled off to the full height of the wall course *d'* shown in Fig. 2. As here shown, the filled in portion E of the dam is divided into apparent sections *e'* by vertical construction joints corresponding to the locations of the bulkhead forms 63 during the filling in operation and to the vertical joints in the wall 20.

Figs. 3, 4 and 5 show the dam as filled in only on the down stream side of the wall D, which thus forms the upstream face of the dam. If desired, additional concrete may be similarly filled in on the upstream side of the wall 20,—thus making the construction a “central wall” one instead of a “facial wall” one. In this case, however, it will usually be preferred to carry along the filling in on the two sides of the wall D more or less concurrently.

While the facial and bulkhead dam forms 60 and 63 may be handled and shifted from the top of the wall D,—as by means of traveling cranes 66, 66 running on the outside rails 21 or even on the outer rails 28,—the lateral distance of the dam face from the wall D may often make it desirable to handle them from closer at hand. As shown in Figs. 2, 8 and 9, the forms 60 and 63 are provided with external supporting brackets 67 and 68 (secured to the angle bars 61 and 64), and on these brackets 67 and 68 are laid tracks or rails 69 extending along in front of the facial forms 60, around the corners, and along in front of the bulkhead forms 63. On this trackway 69 may be mounted traveling cranes or derricks 70 (see Fig. 2) by means of which the form sections 60 and 63 may

be handled and raised, one or more at a time, after disconnection from the rest of the track.

In Fig. 11, I have illustrated the construction of a spillway type of top portion F on a dam by means of traveling form apparatus 73. As shown, this apparatus 73 comprises a truss-built traveler 75 of “straddling” type, with cooperating steel plate dam face forms 76 laterally and vertically adjustable between its legs or sides 77 that rest and run on rails 21 supported by brackets 26 anchored to the subjacent concrete of the dam as already described with reference to Fig. 4. Stay bolt rods 78 (that can be withdrawn after the concrete has set) may extend across between the legs 77 to prevent spreading apart of the forms 76. With adjustment of the wedge blocking or other devices 79 for sustaining the forms 76, the profile of the latter and of the resultant dam top F may be varied as required. With the apparatus 73, such a top F may be built on the dam as shown in Fig. 10, thus increasing its height and giving it a better form of spillway. As shown in Fig. 11, however, the apparatus 73 is set up ready to mold a spillway top F on a lower dam portion G with sloping faces both upstream and downstream,—such as may be built either by the “center wall” method already indicated in connection with Figs. 1-10, or by the simple modification of that method illustrated in Fig. 12, or by the “double wall” method to be described in connection with Figs. 13-15. As shown, the portion G has in its top a broad, shallow channel that will result in interengagement of F and G by a sort of tongue and groove construction joint.

Referring, now, to Fig. 12, it will be seen that along the footing B a rather thick, massive wall D has been built, as by means of the traveling form apparatus illustrated in Fig. 4. A laterally over-hanging truss-built cantilever type of traveler 80 is arranged to run along the top of this wall D, and from one or both of its overhanging ends the dam face forms 81 may be suspended, by means of adjustable hanger rods 82. The dam face forms 81 may be stayed and sustained transversely from the wall D, as by means of stay bolt rods 83 taking into nuts 48 previously embedded in the wall, about as already described in connection with Fig. 7. As here shown, the track 21 for the wheels of the traveler 80 are laid directly on top of the wall D rather than alongside it on overhangng brackets. Ample headroom can easily be provided between the traveler 80 and the top of the wall D, so as to permit the freest use of the pathway afforded by the latter for filling in the concrete at E, E' beside it. When both the face forms 81 shown in Fig. 12 are used,

a lower dam portion G such as shown in Fig. 11 will be produced by the center wall method; while when the form 81 at the left is omitted, a structure more nearly resembling that indicated in Fig. 5 will be produced by a variant of the facial wall method.

In Fig. 13 is illustrated the use of form apparatus 73, 73 such as shown in Fig. 11 to build on the footing B the upstream and downstream facial walls H and H' shown in Fig. 14, and resembling in cross section the dam portions E and E' filled in at either side of the wall D in Fig. 12. As shown, these walls are separated by a space I approximately corresponding in width to the wall D of Fig. 12, and the lower portion of the dam is eventually completed by filling in this space, alongside of each of the walls H, H'. As shown in Figs. 14 and 15, provision

may be made for end closure of the wall space by means of traveling form apparatus 85,—which, by the way, is also applicable for the like purpose in the construction of the wall D of Figs. 1-10 and 12. This apparatus 85 comprises a beam type of traveler 90 which rests and runs along the tops of the walls H and H' over the intervening wall space I, on rails 21 laid directly on them, and a steel plate bulkhead

form 91 suspended from the traveler by means of adjustable hanger rods 95. To facilitate its engagement in vertical dovetail grooves *j* moulded in the walls H and H', and its release therefrom, the steel plate bulkhead form 91 is preferably made collapsible transversely of the wall space I. As here shown, the form 91 is constructed in relatively movable sections, hinged together at 93 to swing and fold horizontally, as indicated in Fig. 15 in dotted lines.

Their adjustable suspension rods 95 are provided with supporting wheels 96 adapted to roll along the beam 90, and are thus relatively movable along the latter, independently of one another, for folding of the form to permit it to be shifted along in the wall space I. As shown, in Fig. 15, the folding portions of the form are individually truss-braced horizontally, and provision is made for bracing them together against undesired outward folding by means of extensible interconnecting turnbuckle-equipped stay rods 97. In the grooves *j*, the ends of the form 91 are wedged fast and firmly sustained by means of blocking 98.

It will be understood, of course, that my invention is applicable to most or all forms and types of dams (such as horizontal arch, beam, etc.), besides the particular forms of the gravity type dam here illustrated. It will also be understood that while I have shown the various portions or blocks of the dam (e. g., the sections *d*, *d'* and *e'* in Figs. 2, 4 and 10, and the portions F and G, D, E, E', and H, H', I in Figs. 11, 12, 14 and

15) as apparently sectionalized or separated by construction joints; yet in practice such parts of a dam will generally be quite effectually keyed, interlocked, or otherwise tied, bonded, or united together (in various ways well understood in the art), so as to render the whole dam virtually monolithic,—or at least give it a unified resistance to stresses like that of a really monolithic dam,—as instance the tongue and groove interengagement amongst the wall sections *d*, *d'* described above.

In various views illustrating different constructions and forms of apparatus, I have marked similar parts and features with the same reference characters as a means of dispensing with merely repetitive description.

I claim:

1. The method for constructing concrete dams and the like, which comprises constructing on the foundation or footing one or more longitudinal walls adapted to form part of the dam sections and to serve as a pathway and means of support in further operations, and then building out the dam section with loose green concrete from and beside such wall or walls.

2. The method for constructing concrete dams and the like, which comprises alternately building upward from the foundation or footing, to a convenient height, a longitudinal wall adapted to form part of the dam section and to serve as a pathway and means of support in subsequent operations, and building up to a corresponding height with loose green concrete from and against such wall.

3. The method for constructing concrete dams and the like by molding green concrete with shiftable forms, which comprises molding on the foundation or footing, with such forms, a longitudinal wall adapted to form part of the dam section and to serve as a pathway and means of support in further operations, and then filling in the loose green concrete from and between such wall and movable dam face forms.

4. The method for constructing concrete dams and the like by molding green concrete with traveling forms, which comprises molding on the foundation or footing, with such forms, a longitudinal wall adapted to form part of the dam section and for the support of other forms and equipment, and filling in the loose green concrete from and between such wall and dam face forms sustained in position therefrom.

5. The method for constructing monolithic concrete dams and the like, which comprises molding on the foundation or footing one or more longitudinal walls adapted for inclusion in the lower portion of the dam section and for the support of concrete conveying and handling equipment,

and building in with loose green concrete the rest of the lower portion of the dam section from and beside such wall or walls.

6. The method of constructing monolithic concrete dams and the like by molding green concrete with shiftable forms, which comprises building the lower portion of the dam on the foundation or footing by progressively molding thereon one or more longitudinal walls adapted to form part of the dam section and to serve as a pathway and means of support in further operations, filling in and molding the rest of the lower portions of the dam section from and beside such wall or walls, and molding the upper portion of the dam on said lower portion as one cross sectional unit.

7. Dam building apparatus comprising a straddling traveller, adapted to run along track carried by a wall, with cooperating wall forms for upward extension of the wall and means for supplying concrete between said wall forms carried by said traveller; shiftable forms for the dam face, with means for anchoring them; and a traveller also adapted to run along such track having means for distributing concrete between said wall and said dam face forms.

8. Dam building apparatus comprising track with bracket means for mounting the same along the sides of a wall; a straddling traveler adapted to run on such track carrying between its sides cooperating wall forms for upward extension of the wall, and also carrying longitudinal track for cars to supply concrete between said wall forms; form sections for the dam face shiftable upward therealong as the dam is filled in behind them, with means for anchoring the sections to the dam in their various positions, and means supported by and movable along them for shifting them as from time to time required; and a traveler adapted to run along the first mentioned track, over car tracks on top of the wall, and having means for elevating concrete from cars on said latter tracks and for distributing it between said wall and said dam face form sections.

9. Apparatus of the character described comprising a straddling traveler with cooperating wall forms between its legs or sides, and track for cars to supply concrete between said forms extending lengthwise of the wall on said traveler.

10. Apparatus of the character described comprising a straddling traveler with cooperating wall forms between its sides or legs, and track for cars to dump concrete between said forms extending along the top of said traveler lengthwise of the wall.

11. Apparatus of the character described comprising a straddling traveler with cooperating wall forms between its sides or legs, and track for cars to dump concrete suspended from the bridge structure of said traveler over the space between said forms.

12. Apparatus of the character described comprising a straddling traveler adapted to run on rails alongside of a wall over car tracks thereon, and means on said traveler for taking concrete from cars on said tracks and distributing it beside said wall.

13. Apparatus of the character described comprising a traveler adapted to run along the top of a wall over car tracks thereon, means on said traveler for elevating concrete from cars on said tracks, and gravitational means for distributing the concrete beside said wall.

14. Apparatus of the character described comprising a straddling traveler adapted to run on rails alongside of a wall over car tracks thereon, and means on said traveler extending upward from beside such tracks for taking and elevating the concrete from cars on the tracks, for distribution beside said wall.

15. Apparatus of the character described comprising a traveller adapted to run along the top of a wall over car tracks thereon; shiftable dam face forms, with means for anchoring them; and means for elevating concrete from cars on said tracks and distributing it between said wall and said forms.

16. In apparatus of the character described, the combination of dam form sections shiftable upward as the dam is erected within them, means for anchoring the sections to the dam in their various positions, a trackway carried by the form sections, and means movable along such trackway for shifting the form sections, as from time to time required.

In testimony whereof I have hereunto signed my name.

CHRISTIAN BRYNOLDT.
